US0D1107713S

(12) **United States Design Patent** (10) **Patent No.:** **US D1,107,713 S**
(45) **Date of Patent:** **** Dec. 30, 2025**

(54) **COVER**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/913,488**

(22) Filed: **Oct. 3, 2023**

Related U.S. Application Data

(63) Continuation of application No. 29/884,947, filed on Feb. 17, 2023, now Pat. No. Des. 1,005,298, which is a continuation of application No. 29/824,061, filed on

Jan. 21, 2022, now Pat. No. Des. 978,867, which is a continuation of application No. 29/797,598, filed on Jul. 1, 2021, now Pat. No. Des. 942,460, which is a continuation of application No. 29/728,326, filed on Mar. 17, 2020, now Pat. No. Des. 924,244.
